COLLAPSIBLE MERCHANDISE DISPLAYING DEVICE

Filed Jan. 24, 1936

UNITED STATES PATENT OFFICE

2,075,657

COLLAPSIBLE MERCANDISE DISPLAYING DEVICE

William S. Powers, New York, and Otto P. Storch,
Ozone Park, N. Y., assignors to The W. F. Powers Company, New York, N. Y.

Application January 24, 1936, Serial No. 60,620

10 Claims. (Cl. 229—41)

This invention relates to devices designed for use in supporting merchandise to be placed on display and particularly packaged goods, such for example, in displaying packages of coffee, 5 cocoa, tea and other beverages, and particularly in providing a device of this class which will represent a cup and saucer and include a back display card or section upon which suitable advertising matter may be applied; and the object of 10 the invention is to provide a device of the character set forth which is made from two blanked pieces of cardboard or similar printed, lithographed or otherwise characterized sheets which when secured together will form a unitary device 15 capable of being compactly folded into a relatively thin package and readily extended and set up for use; a further object being to provide a device of the class described which when opened or extended for use will represent a cup including 20 a handle portion and the representation of a saucer, and a back wall or sheet forming a display section arranged above and continuous with the rear wall portion of the cup; a further object being to provide a device of the character described wherein the bottom wall of the cup proper serves to support the peripheral walls of the cup in extended position, means being provided to reinforce the bottom wall and limit the downward movement thereof so as to form 25 a receptacle within the boundary walls of the cup in which packages of merchandise or articles of merchandise may be placed on display; and with these and other objects in view, the invention consists in a device of the class and for the 30 purpose specified, which is simple in construction, efficient in use, and which is constructed as hereinafter described and claimed.

The invention is fully disclosed in the following specification, of which the accompanying 40 drawing forms a part, in which the separate parts of the improvement are designated by suitable reference characters in each of the views, and in which:

Fig. 1 is a plan view of a device made according to our invention with part of the construction broken away, the device being shown in extended position.

Fig. 2 is a front view of a device shown in Fig. 1 with part of the structure broken away 50 and in section.

Fig. 3 is a plan view of one blank from which the device is formed.

Fig. 4 is a plan view of another blank which we employ; and,

Fig. 5 is a sectional view on the line 5—5 of

Fig. 2 showing the device in collapsed position.

In carrying the invention into effect, two blanks are employed, one blank being represented at 10 in Fig. 3 of the drawing and the other at 11 in Fig. 4. The blank 10 consists of a central back portion 12 which forms the back wall of the cup portion 13 of the display, and this wall includes an extension 14 forming a display card or tube upon which any suitable advertising or other literature may be printed, 5 lithographed or otherwise applied. It is understood in this connection that all of the parts of the resulting device may be printed, colored or characterized to represent the intended article, such for example as the cup and saucer in order 10 to produce a very attractive appearance.

The blank 10 also includes side wall portions 15, 16, foldable with respect to the back wall 12 and having foldable flanges 15a, 16a at the free edges thereof for attachment to the side wall 20 portions 17, 18 of the blank 11 in the manner clearly illustrated in Fig. 1 of the drawing. The side wall 18 of the blank 11 also has a foldable cut out 19 which represents the handle of a cup, and this handle is adapted to extend outwardly from the side of the cup in the manner illustrated in Figs. 1 and 2 of the drawing. The central portion 20 of the blank 11 forms the front wall of the cup and this wall has at its lower end a foldable flap 21 having a cut out 30 tongue portion 22, the latter being foldable beneath the front portion of the bottom or saucer part 23 to secure the front wall 20 to the front portion of the saucer part 23; whereas, the flap 21 is folded in an opposite direction to the 35 tongue 22 and extends onto the lower surface of the saucer 23 beneath the side walls 17 and 18 and is glued or otherwise secured thereto as is indicated at 21a at the left of Fig. 1 of the drawing. This flap forms a bottom stop wall between 40 the lower ends of the walls 17 and 18. This stop wall limits the downward movement of the hexagonal bottom wall 24 formed from the blank 10 and foldable on the line 25 with respect to the back wall 12 of said blank, said wall having extending wings 12a at the sides thereof which are foldable with respect to the rear portions 23a of the saucer 23. The portions 23a are also foldable with respect to the front part of the saucer along the lines 23b when the device is in 50 collapsed position.

The hexagonal bottom wall 24 is cut from the central portion of the saucer forming part, and when the two blanks are secured together in the manner seen in Figs. 1 and 2 of the drawing, 55

the bottom wall 24 fits snugly within the lower edge of the front wall 20 so as to frictionally and tensionally support the cup in extended position. Slight openings will be formed between 5 the lower curved edges of the side walls 15, 16 and the parts 23a of the saucer equal to the thickness of the lower extensions 12a. However, the forward edges of the walls 15 and 16 will rest upon the surface of the saucer part 23 adjacent 10 the fold lines 23b.

When the device is set up or extended for use, it will represent a cup and saucer with the advertising or display card extending upwardly from the back wall 12 and beyond the side edges 15 of the back wall, and various articles or packages of merchandise, such for example as various beverage making substances may be placed within the cup and exposed through the upper surface thereof, in other words, forming a display 20 container or receptacle for the merchandise which is being offered for sale. The display section or part 14 may have any desired irregular contour to produce any particular or desired effect in the resulting display. In the accompanying drawing, the upper right hand corner is indicated with an irregular cut out which will be representative of a part of a display printed or otherwise formed upon the surface of this section.

30 In collapsing the device, all that it is necessary to do is to remove the articles from the cup and then lift the bottom wall 24, then move this wall together with the front wall 20 upon the back wall 12, in which operation, the walls 15, 17, 18 and 19 collapse one upon the other and the forward part of the saucer 23 folds upon the walls 17, 18 and 20 as well as upon the parts 23a forming a package equal in thickness to the thickness of the representative sheets or wall portions as 40 arranged one upon the other. In this way, the device may be compactly packed and shipped for transportation and readily set up for use by simply moving the bottom wall 24 forwardly in extending the parts as previously stated.

45 Our invention is not necessarily limited to the particular contour of the device herein shown and described, nor is the device limited to any particular use, the distinctive feature of the invention residing in the arrangement of the container portion with the bottom skirt or saucer portion as an integral part of the complete display. The projecting advertising sheet or section may be arranged in any desired manner and of any suitable contour. It will also be apparent 55 that the bottom skirt or saucer portion forms a large supporting base for the display device.

Having fully described our invention, what we claim as new and desire to secure by Letters Patent, is:

60 1. A collapsible display device comprising two blanks, one of said blanks having centrally thereof of three foldably related side wall parts, the central part having a disk-like extension at one edge thereof, said extension having a substantially hexagonal cut-out portion forming a bottom wall part, the other blank consisting of three side wall parts the central wall part having means extending from one side thereof and adapted to engage and be secured to the disk 65 part of the first named blank, means for securing the outer side edges of the side wall parts of each blank together to form a substantially hexagonal cup-shaped body arranged upon and substantially within the peripheral boundaries of said disk part, said bottom wall part being arranged within said cup-shaped body and serving to support said body and the device as a whole in extended position, one side wall of one of said blanks including an integral upwardly directed extension forming a display portion, 70 another of said side wall parts having a laterally projecting integral part fashioned to represent a handle portion, the means on the second-named blank secured to said disk part comprising a wide flange portion and a tongue portion cut therefrom both arranged upon and secured to the lower surface of said disk part.

arranged within said cup-shaped body and serving to support said body and the device as a whole in extended position.

2. A collapsible display device comprising two blanks, one of said blanks having centrally thereof of three foldably related side wall parts, the central part having a disk-like extension at one edge thereof, said extension having a substantially hexagonal cut-out portion forming a bottom wall part, the other blank consisting of three side wall parts the central wall part having means extending from one side thereof and adapted to engage and be secured to the disk part of the first named blank, means for securing the outer side edges of the side wall parts of each blank together to form a substantially hexagonal cup-shaped body arranged upon and substantially within the peripheral boundaries of said disk part, said bottom wall part being arranged within said cup-shaped body and serving to support said body and the device as a whole in extended position, and one side wall of one of said blanks including an integral upwardly directed extension forming a display portion.

3. A collapsible display device comprising two blanks, one of said blanks having centrally thereof of three foldably related side wall parts, the central part having a disk-like extension at one edge thereof, said extension having a substantially hexagonal cut-out portion forming a bottom wall part, the other blank consisting of three side wall parts, the central wall part having means extending from one side thereof and adapted to engage and be secured to the disk part of the first named blank, means for securing the outer side edges of the side wall parts of each blank together to form a substantially hexagonal cup-shaped body arranged upon and substantially within the peripheral boundaries of said disk part, said bottom wall part being arranged within said cup-shaped body and serving to support said body and the device as a whole in extended position, one side wall of one of said blanks including an integral upwardly directed extension forming a display portion, and another of said side wall parts having a laterally projecting integral part fashioned to represent a handle portion.

4. A collapsible display device comprising two blanks, one of said blanks having centrally thereof of three foldably related side wall parts, the central part having a disk-like extension at one edge thereof, said extension having a substantially hexagonal cut-out portion forming a bottom wall part, the other blank consisting of three side wall parts, the central wall part having means extending from one side thereof and adapted to engage and be secured to the disk part of the first named blank, means for securing the outer side edges of the side wall parts of each blank together to form a substantially hexagonal cup-shaped body arranged upon and substantially within the peripheral boundaries of said disk part, said bottom wall part being arranged within said cup-shaped body and serving to support said body and the device as a whole in extended position, one side wall of one of said blanks including an integral upwardly directed extension forming a display portion, another of said side wall parts having a laterally projecting integral part fashioned to represent a handle portion, the means on the second-named blank secured to said disk part comprising a wide flange portion and a tongue portion cut therefrom both arranged upon and secured to the lower surface of said disk part.

5. A display container of the class described comprising a hollow cup-shaped body including a base portion integrally formed with a part of the wall portion of said body, said base extending outwardly beyond the peripheral edges of said body when the container is in open position, said body and base portion being collapsible into a relatively thin package, a bottom wall cut from the material of the base portion and of a contour conforming with the contour of the lower end portion of said body, said bottom wall being foldable with respect to said base portion, and said bottom wall frictionally engaging the walls of said body when in open position to support said body in such position. 15

6. A display container of the class described comprising a hollow cup-shaped body including a base portion integrally formed with a part of the wall portion of said body, said base extending outwardly beyond the peripheral edges of said body when the container is in open position, said body and base portion being collapsible into a relatively thin package, a bottom wall cut from the material of the base portion and of a contour conforming with the contour of the lower end portion of said body, said bottom wall being foldable with respect to said base portion, said bottom wall frictionally engaging the walls of said body when in open position to support said body in such position, and one side wall of said body having an integral, outwardly projecting part in the form of a handle portion. 30

7. A display container of the class described comprising a hollow cup-shaped body including a base portion integrally formed with a part of the wall portion of said body, said base extending outwardly beyond the peripheral edges of said body when the container is in open position, said body and base portion being collapsible into a relatively thin package, a bottom wall cut from the material of the base portion and of a contour conforming with the contour of the lower end portion of said body, said bottom wall being foldable with respect to said base portion, said bottom wall frictionally engaging the walls of said body when in open position to support said body in such position, one side wall of said body having an integral, outwardly projecting part in the form of a handle portion, and one wall of said body having an upwardly projecting integral display portion. 45

8. A device of the class described fashioned from two blanks of sheet material, each of said blanks having foldable wall parts, means joining adjacent ends of said parts to form continuous 50 side walls of a cup-shaped body, one wall of one

of said blanks having an integral disk part, the peripheral edges of which project beyond the corresponding edges of said body when in extended position to form a base or saucer for said body, a bottom wall cut from the material of said disk part and foldable with respect thereto, said bottom wall being arranged within and forming a closure for said body as well as means for supporting said body in extended position, and means on the other of said blanks for securing the lower portion of the walls thereof in abutting relation to said disk part. 5

9. A device of the class described fashioned from two blanks of sheet material, each of said blanks having foldable wall parts, means joining adjacent ends of said parts to form continuous side walls of a cup-shaped body, one wall of one of said blanks having an integral disk part, the peripheral edges of which project beyond the corresponding edges of said body when in extended position to form a base or saucer for said body, a bottom wall cut from the material of said disk part and foldable with respect thereto, said bottom wall being arranged within and forming a closure for said body as well as means for supporting said body in extended position, means on the other of said blanks for securing the lower portion of the walls thereof in abutting relation to said disk part, and the walls of one of said blanks having an integral, outwardly projecting handle portion. 10

10. A device of the class described fashioned from two blanks of sheet material, each of said blanks having foldable wall parts, means joining adjacent ends of said parts to form continuous side walls of a cup-shaped body, one wall of one of said blanks having an integral disk part, the peripheral edges of which project beyond the corresponding edges of said body when in extended position to form a base or saucer for said body, a bottom wall cut from the material of said disk part and foldable with respect thereto, said bottom wall being arranged within and forming a closure for said body as well as means for supporting said body in extended position, means on the other of said blanks for securing the lower portion of the walls thereof in abutting relation to said disk part, the walls of one of said blanks having an integral, outwardly projecting handle portion, the walls of one of said blanks including an upwardly projecting display section, and said disk part being folded on a line registering with the intersecting ends of the respective blanks. 15
